Specification of Letters Patent. Patented Nov. 23, 1920.

Original application filed December 31, 1914, Serial No. 879,912. Divided and this application filed May 31, 1917, Serial No. 171,981. Renewed August 3, 1920. Serial No. 401,083.

To all whom it may concern:

Be it known that I, FRIEDERICH MÜLLER, a citizen of the United States, residing at Hartford, in the county of Hartford and State of Connecticut, have invented certain new and useful Improvements in Metallic Bushings and Similar Cylindrical Bodies, of which the following is a specification.

This application is filed as a division of 10 my prior application, Serial No. 879,912, filed December 31, 1914.

My invention relates broadly and generally to new and useful improvements in metallic bushings and similar cylindrical bodies, as an article of manufacture.

An important object of the invention, among others, is to produce a bushing which will be adapted for general use in the mechanical arts, but which will be particularly 20 desirable for use in connection with power transmission chains, for instance, the well-known form of sprocket chains, and also of the link-belt type, which bushing may be made economically and rapidly from a blank 25 of suitable metal, and which will have the advantages of being truly cylindrical both exteriorly and interiorly, which will have the grain of the metal extended circumferentially thereof, strengthening the same against fracture under strain, and which will be of such 30 form as to facilitate the assembling of the same in the completed chain structure, particularly in connection with a machine for automatically applying said bushings to said 35 chains, or the elements of chains.

The invention consists in the improvements to be more fully described hereinafter, and the novelty of which will be particularly pointed out and distinctly claimed.

40 I have fully and clearly illustrated in the accompanying drawings, to be taken as a part of this specification, the improved bushing view of a preferred embodiment of the machine for carrying out the method for producing said bushing.

In said drawings, Figure 1 is a top plan view of a preferred embodiment of the machine, certain parts being broken away to better disclose the operation and arrangement of certain parts thereof.

Fig. 2 is a vertical section on the line 2—2 of Fig. 1 looking in the direction of the arrows.

Fig. 3 is a section on the line 3—3 of Fig. 1. Fig. 4 is a view in end elevation of a portion of the machine shown in Fig. 1, and illustrating mechanism for operating a transfer slide.

Fig. 5 is a view in rear elevation and partly in section, of a portion of the machine 60 showing the arrangement of the transfer slide operated by the mechanism shown in Fig. 4, and also a slide for operating a mandrel.

Fig. 6 is a horizontal sectional view of a 65 portion of the machine showing the location of a slide member for subjecting a blank to a curling or forming die, certain parts being removed and the transfer slide shown in position to receive the stock when it is fed 70 through the guide block and cut-off.

Fig. 7 is an enlarged sectional detail view of a stripping device.

Fig. 8 is a front view of the transfer slide showing the same in the position it assumes 75 after removing the blank from the cutting knife and presenting the same to the curling or forming die.

Fig. 9 is an enlarged detail view of the 80 transfer slide.

Fig. 10 is an enlarged sectional view through the transfer slide and showing the curling or forming die, and a sectional view of the mandrel located in said curling or forming die.

Fig. 11 is an enlarged vertical section through the transfer slide block showing the cutting knife and its carrier, and the spring means for raising the same after the cutting operation.

Fig. 12 is an enlarged vertical sectional view through roller means for forming and sizing the bushings.

Fig. 13 is an enlarged view in side elevation of the sizing block and showing a stock 95 plate to guide flat stock as it is being pushed into the curling or forming die.

Fig. 14 is a vertical sectional view of a modified form of the invention for feeding the stock in the form of previously cut blanks 100 from the hopper to the curling or forming die.

Fig. 15 is a sectional view on the line 15—15 of Fig. 14.

Fig. 16 is a sectional view showing another 105 means for cutting off the stock from a con-

tinuous strip and presenting it to the slide for moving it into the curling or forming die.

Fig. 17 is a section taken on the line 17—17 of Fig. 16 and showing the cutting-off plunger in lowermost position to serve as the guide for the stock as it is pushed into the curling or forming die.

Fig. 18 shows a plan and side elevation of 10 the blank of metal from which the bushing is made, and previous to being curled.

Fig. 19 is a view in end elevation of the blank previous to being curled and showing the rounded edges thereof.

Fig. 20 shows the position assumed by the 15 blank after being subjected to the action of the curling or forming die.

Fig. 21 shows the position assumed by the 20 blank after being subjected to the forming rollers.

Fig. 22 is an end view of the completed bushing after it has been passed through the curling or forming die, the forming rollers and the sizing bushing or die.

Fig. 23 is a longitudinal section through 25 the finished bushing.

I will now describe my improved bushing and the method of producing the same. I do not claim the method herein, but do claim 30 the same in the parent application Serial No. 879,912, filed December 31, 1914, of which this present application is a division. The apparatus is made the subject-matter of 35 another divisional application filed under even date herewith.

According to one way of producing my improved bushing, I take a strip of metal stock of the desired nature, and in which the fibers or grain extend lengthwise of the strip, 40 and provide one or both, preferably both, side edges thereof with rounded surfaces as indicated at *a* in Fig. 18 in the drawings, and from this strip cut a blank on a line extending transversely of the strip entirely across 45 the same so as to produce a rectangular blank having two of its opposite parallel sides rounded, and the two other parallel sides cut at an incline to the plane of the blank as indicated at *b*. This blank is of such dimensions that its width from one rounded edge to the other will produce a bushing of corresponding length, and of such width from one inclined edge to the other that a bushing of the desired diameter and bore will be produced. I then take this blank and by a curling operation curl it on an axis extending 50 parallel to the inclined or transverse sides, which produces a tubular body substantially similar to the body shown in end elevation 55 in Fig. 20 of the drawings. In this condition the inclined edges do not meet and a true cylinder is not produced. In performing this curling operation I prefer to wrap the metal blank about a mandrel or core 60 located within a cylindrical die member by

forcing the blank with one of its inclined edges foremost into said die, and about the core by a movement at right angles to the longitudinal axis of the die and core, whereby the blank is by its engagement with the 70 cylindrical surface of the die forced to curl or wrap about the core. A preferred form of this die and core will be described in detail hereinafter.

Upon completion of the curling operation 75 I subject said body so curled, and while still on the mandrel, to a compression operation whereby the meeting inclined edges are forced into engagement with each other and a true cylindrical contour is given to both 80 the bore and the circumference of said body. I accomplish this preferably by forcing said body, such as shown in Fig. 20, and while still on the mandrel, through a pair of compression die rollers which press and shape 85 said body to substantially the form shown in Fig. 21, in which the bushing is substantially cylindrical, but the cut edges of the blank are slightly spaced apart and parallel to each other. The body in the form shown 90 in Fig. 21, and while still on the core or mandrel, is then forced through a suitable compression die, which contracts the cylinder until it reaches the true cylindrical form shown in Fig. 22, in which the meeting edges 95 abut. In this condition the bushing is completed and is in condition for use in any situation desired. It will be noted that in producing this bushing the inclined cut edges in the completed article abut so as to 100 lie in a plane substantially radial to the longitudinal axis of the bushing. It will also be seen that in the completed article the fiber or grain of the metal extends about the bushing circumferentially which is of great advantage in that this arrangement of the fibers provides a tough and more rigid bushing, which is not liable to be splintered under blows or strains, this being due to the 105 fact that the bushing is not brittle as the case would be where the grain of the metal runs longitudinally of the bushing. The rounded ends of the bushing are of advantage because it is not necessary to mill or reduce the same in order to insert the bushing through openings in chain links, as the 110 case would be where the bushings have squared ends, which are liable to have fins or spurs of metal interfering with the insertion of the bushing, and which must be removed before assembling the bushing in a 115 chain structure. The rounded ends will be found especially advantageous when used in a chain assembling machine, as the bushings can be readily fed to the chain and assembled 120 therein without regard to the form of the ends of the bushing. The action of the dies in compressing and forming the blank, results in the metal of the starting blank 125 being drawn, stretched or flowed so that the 130

finished product is of greater length than the width of the starting blank, and its circumference is greater than the length of the blank.

- 5 I will now proceed to describe the machine for carrying out the method and producing the improved bushing above described. Referring to the drawings, and particularly Figs. 1, 2 and 5 thereof—
- 10 1 designates a machine frame, the construction of which may be varied widely without affecting the scope of my invention, but preferably consisting of two wings or sections 2, 3 arranged at right angles to each other, and a short wing or section 4 at right angles to the part 1 and extending in opposite directions from, and in longitudinal alignment with, the part 3. Mounted on the upper portion of the frame between the parts 3 and 4 is a fixed block 5, bolted to the bed plate of the frame as at 6, and provided with a vertical opening 7, in which is arranged for vertical reciprocation, a knife block or carrier 8, having a central vertical opening 9 in which is secured a chisel knife 10, the lower chisel end of which depends from said block 8 and cooperates with an anvil plate 12 secured in a recess 13 in the bottom wall of the opening 7 in said block 5. The knife may be secured in the block 8 in any suitable manner as by a set screw 14 threaded through said block and engaging said knife with its inner end. This knife has a double inclined chisel end, as indicated in Fig. 2 for a purpose to be presently set forth. The knife block or carrier 8 is normally urged upward by a pair of expansion springs 15, the ends of which respectively abut the bottom of the opening 7, 40 on opposite sides of the plate 12, and the lower portion of said block or carrier 8. By this means the carrier is automatically raised to locate the cutting edge of the knife at a point above the plate 12. The knife carrier or block is held in place in the opening 7 by keeper plates 7^a, and is normally thrust laterally against said plates by means of a spring 8^a exerting its force expansively against the back wall of said opening 7, 50 and the vertical face of the knife carrier 8, the sidewise movement being at right angles to the line of cut, as will be clear from Fig. 2. The particular function of this arrangement will be presently described. The plate or block 12, heretofore described, is provided with a longitudinal passageway 16 leading to a point beneath the cutting edge of the knife, and opening through the opposite side of the block 5 from that on which 60 the knife reciprocates, and adapted to guide a strip of stock to the knife so that the latter may sever the necessary portion to form a blank for a bushing. The strip of stock may be fed to the knife in any suitable manner, but I prefer to employ the means shown

to the left of Figs. 1, 2, 4 and 5. In this form of feeding means I provide upper and lower feed rollers, 17, 18 having bearings in pedestals 19, mounted on the extension 4 of the machine frame. The upper of these 70 rollers carries a gear 20 in mesh with a gear 21, mounted on a stub shaft 22 secured to one of the pedestals 19, said gear 21 having connected therewith a pawl and ratchet clutch mechanism 23, the operating lever 24 75 of which is reciprocated by a connecting rod 25 connecting said arm to a rock lever 26 fulcrumed on the frame as at 27, and having a cam follower pin 28 engaging an eccentric cam groove 29 on a rotatable cam disk 80 30 mounted on a horizontally disposed power shaft 31. The power shaft is mounted in suitable bearings on the frame and may be driven continuously in one direction by any suitable means. It will be apparent 85 that the construction of the feeding means is such as to intermittently feed the strip of stock forward step by step to the knife.

Mounted on the frame, and in line with the part 2, and spaced from the block 5 and 90 the knife 10 is a transversely arranged block, hereinafter referred to as a die block 32, having a vertical stop face 33 against which the inner end of the strip of stock abuts previous to being cut off by the knife, 95 so that the strips cut will always be of a determined length, the length of blank cut corresponding to the distance from the knife edge to said face 33. This length may be regulated by providing said stop face 100 with removable plates 34 of different thicknesses, adapted to be secured to the die block by bolts 35, whereby the said stop face can be located at different distances from the line of cut. It will also be understood that the feeding connections may be 105 adjusted to regulate the amount of strip fed to the knife to correspond to the distance from the line of cut to said cut-off.

Arranged to reciprocate across the outer 110 face of the knife 10, and between the block 5, and the block 32, is a reciprocable transfer slide 37 having a dovetail sliding connection 36 with a dovetail groove in the vertical face of the block 5. This transfer 115 slide in retracted position extends by the knife and the opening 16, and is provided with a slot 38 to receive the end of the strip being severed, and transfer the same to a forming die to be presently described. 120 This transfer slide in its retracted position, is arranged with said slot in line with the line of feed of the strip of stock, so as to receive that end portion of the strip which is to be severed and which abuts the face 125 plate 34. The transfer slide is timed to transfer the severed portion of the strip, which is to be formed into the bushing, to a point to one side of the knife and so as to bring its slot 38 in line with a forming or 130

curling slide 39, which reciprocates at right angles to the path of movement of the transfer slide 37 and moves the metal blank to the curling or forming die. The transfer slide is also formed with a vertical slot 40 opening through the bottom edge of the slide into said slot 38, for a purpose to be presently set forth. The curling or forming slide consists of a bed portion 41 sliding in guideways 42 in the main frame from which rises a vertical blade member 43, the upper edge portion of which is adapted to reciprocate through the vertical slot 40 formed in the transfer slide and to project up far enough to engage the metal blank in the slot 38 to dislodge said blank from said transfer slide, substantially as shown in Figs. 6, 8 and 10 of the drawings.

I will now describe the curling or forming die into which the metal blank is forced by the curling or forming slide 39, to be curled to the form shown in Fig. 20 of the drawings. For this purpose the die block 32 is formed with a horizontal cylindrical bore 44 extending at right angles to the line of reciprocation of the curling or forming slide, and at an intermediate point of this bore is located a cylindrical die bushing 45 held by guide bushings 46, 47, arranged in said cylindrical bore on opposite sides of the cylindrical die, the bushings 46, 47, being held in position by set screws 48 threaded through the upper portion of said block 32. This cylindrical die bushing 45 is open at one edge through a slot 49 substantially tangential to the circumference of the internal cylindrical wall of the die, as clearly shown in Fig. 10 of the drawings. The arrangement of the die and curling slide is such that when the metal blank is dislodged from the transfer slide and pushed forward by the curling slide, said blank will be pushed through the slot or opening 49 by the curling slide and curled up against the inner cylindrical surface of the curling die, the blade 43 of the curling slide entering the said slot 49, so that the entire metal blank is passed into the cylindrical bore of the curling die 45. The die block 32 may be recessed adjacent the entrance to the die, as 32^a, to receive a guide member 32^b bolted to the die block and having horizontal parallel spaced arms 32^c upon which the blank slides from the transfer slide to the die when moved by the curling slide blade 43, said blade 43 moving between said arms.

Arranged to slide in the said bore 44 through the die block 32, is a combined pusher and mandrel or core 50 carried by a reciprocating bed 51, sliding in guideways 52, on the frame part 3, said mandrel or core being adapted to reciprocate through the sleeve 47 heretofore described, closely fitting the bore of the same, and having at its end 65 a reduced cylindrical core part 53 which,

when the mandrel is in one position, is located centrally of the cylindrical curling die 45, so that said core part 53 forms a mandrel or core about which the metal blank is curled in the space between the part 53, 70 and the inner wall of the curling die 45 when said blank is forced into the die 45 by the curling slide 39.

It will be understood that the feeding mechanism, the knife, the transfer slide, curling slide, and the mandrel are so timed in their movements that the strip will be presented to the knife; then severed by the knife, whereupon it will be moved by the transfer slide into the path of movement of the curling slide, and the curling slide will then force it into the curling die 45 around the core portion 53 of the mandrel, the mandrel-moving means having a dwell for a period sufficient to hold the core-piece 53 in the die 45 during the curling of the blank, and the transfer slide having a dwell long enough for the curling slide to pass through the same in forming the blank to the die, and then return to initial position. Any suitable means may be provided for producing the sequence of movements just set forth, which means may be varied without departing from the spirit and scope of my invention. 95

I will now proceed to describe one way of operating the knife to cut the strip. Mounted on the part 3 of the frame is a standard comprising vertical spaced arms 54 upon which is fulcrumed a rock lever 55 adapted to engage the upper portion of the chisel knife to move the same downward to engage the strip to cut off a bushing blank. I preferably provide an adjustable engagement between one end of said lever and the knife, 100 the same comprising a thrust bolt 56 threaded through the lever and adapted to engage with its lower end upon the upper end of the knife, so that when the said lever is rocked in one direction, the knife will be moved down to sever the strip, and when the lever is moved in the opposite direction, the springs 15 will act on the carrier block to raise the knife. The forward end of the lever is also provided with a stop screw 57 threaded therethrough and adapted to engage the upper surface of the block 5 to limit downward movement of the lever so that the knife in its downward movement will just meet the block 12, and not cut into 110 the same or be dulled thereby. The lever may be timed by any suitable means so as to descend subsequent to the feeding of the strip, and for this purpose a reciprocating plunger 58, sliding in a vertical guide 59 115 on the main frame and operated by an eccentric cam 60 on the shaft 31, may be employed.

The transfer slide 37, may be reciprocated by a lever 61 carried by a horizontal rock 120

shaft 62, and having its free end in engagement with a pin 63, connected to the said slide and projecting laterally therefrom through a slot 64 in the block 5. The shaft 62 is rocked by an arm 65 connected thereto and engaging a cam groove 66 in the cam disk 30 heretofore described.

The curling slide may be operated by a grooved cam 67 mounted on the shaft 31, and 10 engaging a pin 68 carried by the base piece of said curling slide, and the mandrel may be operated by a bell-crank lever 69, fulcrumed on the frame as at 70, and having one of its arms 71 pivotally engaging the 15 mandrel carrier or bed 51 as at 72, and its other arm 73 provided with a pin 74 engaging a grooved cam 75 also mounted upon the shaft 31 to rotate therewith. So far the time relation of the parts described, is as 20 follows: The feeding mechanism feeds the strip forward a distance sufficient to supply one bushing blank, whereupon the knife 10 descends, severing the blank from the strip, then the transfer slide 37 moves the 25 severed blank away from the knife into the path of movement of the curling slide 43, and the latter then moves forward to engage the blank and force the same into the curling die 45, and around the core-piece 30 53 of the mandrel 50.

The lateral sliding movement of the knife carrier, in the form shown in Fig. 2, is provided so that when the knife descends it may have sufficient lateral play to produce the 35 inclined edge on the rear of the blank cut-off, and also on the forward edge of the strip of stock. The lateral movement also permits the carrier and knife to move back from the cut blank so as not to jam or bend the 40 same against the stop face on the block 32, due to the chisel knife forcing the strip of stock and the cut blank away from each other.

These parts then return to their natural 45 positions for the cutting and transfer of the metal blank, during which period the mandrel 50 with the core-piece 53 moves forward with the curled metal blank and forcing the latter through a pair of upper and lower 50 compressing and forming die rollers 76, arranged in the bore 44, whereby the metal blank in the form shown in Fig. 20 is reduced to the form shown in Fig. 21, and the mandrel 50 continues its movement carrying 55 the blank in the form shown in Fig. 21 into a tapered die bushing 77 in longitudinal alinement with the die 45, whereby the bushing blank is compressed and shaped to the form shown in Fig. 22, which is the completed commercial article. In the forward movement of the mandrel, the shoulder 53^a, engages one end of the bushing curled on the core-part 53, so that the proper thrust is given the bushing to carry it through the 60 rollers 76 and the die 77. After being sub-

jected to the action of the tapered die bushing 77, the bushing is carried on still farther by the mandrel until it reaches a stripping chuck 78 having spring hook arms 79 which catch over the rear end of the completed 70 bushing and holds the latter so that when the mandrel 50 is retracted to its initial position, as shown in Figs. 1, 3 and 6, the completed bushing is stripped from the core portion 53 of the mandrel. As soon as the 75 mandrel is returned to its initial position, the feeding mechanism, knife, a transfer slide and curling slide, repeat the operation heretofore described to again curl the blank about the core portion of the mandrel, and 80 the latter then forces the curled blank successively through the compressing or forming rollers, and the tapered die to the stripping chuck.

In the forms of the invention shown in 85 Figs. 14 and 15, the cutting mechanism and the transfer slide, and its operating mechanism may be omitted, because the blanks from which the bushings are to be made, are previously cut by other means. In this 90 form of the invention I provide a hopper arranged over the pair of separated supports or arms 32^c spaced from the bottom of said hopper, substantially the thickness of the blank, and adapted to support a 95 stack 79^a of previously cut blanks arranged one above the other in the hopper, and adapted to gravitate one by one onto said support in the path of movement of the curling slide. In this arrangement, the curling slide 39 reciprocates between the spaced 100 supporting members or arms 32^c, and removes one blank at a time from the bottom of the stack in the hopper and forces the blank into the curling die for the purpose 105 heretofore described.

In Figs. 16 and 17, as shown, a further embodiment of the invention in which the transfer slide is dispensed with, and the cutting member transfers the cut blank 110 from a strip into position to be engaged by the curling slide to be presented to the curling die. In this form, a cutting plunger 80 is arranged in the block 32 to reciprocate by, and shear against, the vertical squared end of that portion of the block 5 through which the strip of stock is fed, said cutting block being urged to retracted position by a spring 81, and moved to shear the metal by the same means shown in Figs. 1, 2, 3 and 115 5. In its downward movement, the cutting blank moves the cut metal blank down into the upper surface of spaced guide members 32^c, from which point it is moved by the curling slide into the curling die in 120 the same manner as heretofore described. The machine above described is adapted for manufacturing bushings of various sizes within limits, by merely interchanging the die bushings so as to provide one of the 125 130

diameter to produce a bushing of the desired size, and by the interchange of mandrels with core-pieces corresponding to the bore of the bushing. At the base of the 5 core part 53 is a shoulder 53^a, which serves a purpose already described.

It will be understood that, in small bushings wherein the metal stock is necessarily thin, it will not be obligatory to provide the 10 inclined edges on the blank before curling. In this case the shearing means shown in Figs. 16 and 17 may be employed.

What I claim and desire to secure by Letters Patent of the United States is:

15 1. A bushing consisting of a cylindrical body having the grain of the metal directed circumferentially, and having a rounded end.

20 2. A bushing consisting of a cylindrical body having the grain of the metal directed circumferentially, and having its opposite ends rounded.

25 3. A bushing consisting of a cylindrical body made from a blank of metal, the edges of which meet along a line extending lengthwise of the body, and in which the grain of the metal extends circumferentially, said body having rounded ends.

4. A bushing consisting of a cylindrical

body made from a blank of metal, the edges 30 of which meet along a line extending lengthwise of the body and in which the grain of the metal extends circumferentially of the bushing and is compressed during the forming operation. 35

5. A bushing consisting of a cylindrical body made from a blank of metal, the edges of which meet along a line extending lengthwise of said body in which the grain extends circumferentially, said bushing being of greater length than the width of the blank from which the same is formed. 40

6. A bushing consisting of a cylindrical metallic body having the grain of the metal directed circumferentially of the bushing. 45

7. A bushing consisting of a cylindrical body made from a blank of metal, the edges of which blank meet along a line extending lengthwise of the body, and in which the grain of the metal extends circumferentially of the body. 50

In testimony whereof I have hereunto signed my name in the presence of two subscribing witnesses.

FRIEDERICH MÜLLER.
